UNITED STATES PATENT OFFICE.

EDWIN EDELSTEIN, OF ELGIN, ILLINOIS, ASSIGNOR TO ILLINOIS WATCH CASE COMPANY, OF ELGIN, ILLINOIS, A CORPORATION OF ILLINOIS.

DESIGN FOR A WATCH HOLDER.

Application filed February 15, 1926. Serial No. 16,524. Term of patent 3½ years.

To all whom it may concern:

Be it known that I, EDWIN EDELSTEIN, a citizen of the United States, residing at Elgin, in the county of Kane and State of Illinois, have invented a certain new, original, and ornamental Design for Watch Holder, of which the following is a specification, reference being had to the accom-

panying drawing, forming part hereof, wherein is illustrated a perspective view of a watch holder showing my new design.

I claim:

The ornamental design for a watch holder as shown.

EDWIN EDELSTEIN.
